UNITED STATES PATENT OFFICE.

HARRY T. McBRIEN, OF CLEVELAND, OHIO, ASSIGNOR TO UNDERWOOD TYPEWRITER COMPANY, OF NEW YORK, N. Y., A CORPORATION OF DELAWARE.

TYPEWRITING MACHINE.

Application filed June 28, 1921. Serial No. 480,964.

To all whom it may concern:

Be it known that I, HARRY T. McBRIEN, a citizen of the United States, residing in Cleveland, in the county of Cuyahoga and State of Ohio, have invented certain new and useful Improvements in Typewriting Machines, of which the following is a specification.

This invention relates to means for holding a large stiff card, or the like, in proper relation at the writing line with the revolute platen of a front-strike typewriting machine, and is herein illustrated as applied to an Underwood Standard typewriter.

For certain kinds of work, for example, the keeping of savings bank accounts, it has been customary to use large cards for individual accounts, each card being introduced into the typewriter each time an entry is to be made thereon, usually only one entry being made for a given date. The card in each case has usually been introduced at the front of the platen, while the feed-rolls were released, and brought to proper typing position. The feed-rolls have then been restored and the usual card-guide, pivoted upon the front bar of the typewriter carriage, swung back to hold the card against the platen at the printing line. Owing to the stiffness of the cards, each card has necessarily been held against the platen by some such means as the card-guide, since otherwise the card would not lie closely against the platen at the printing line, and, when struck by a type, would be moved slightly, thereby preventing good type impressions. It will be seen that the card-guide must be moved to one side each time a card is to be inserted at the front of the platen and must then be shifted to its effective position before typing on a card. Obviously, the operation of moving the card-guide back and forth interferes with rapid work.

The main object of the invention is to provide improved card-controlling means by which a card in use will be held in proper position against the platen at the printing line, and which will permit the introduction and arrangement of a card in printing position more rapidly than heretofore, thereby enabling a higher speed of operation. Other objects of the invention are to provide card-controlling means simple in form, economical to manufacture, efficient

in operation, readily applicable to existing machines, and attractive in appearance.

According to this invention, the use of the aforesaid swinging card-guide is unnecessary, and the means for holding the card at the delivery side of the platen is stationary with respect to the platen-frame, thus avoiding any delay which would result if any shifting of parts were necessary.

In carrying out the invention, provision may be made of a plate or support above the platen bent upwardly at one end, preferably at the left, to form a flange or side-edge gage which may be used in aligning a card with reference to the platen. An arm is bent from the gage at its upper edge and extends to the right, parallel to the plate, and at its free end the arm is bent downwardly to form a card-holding finger, sufficient space being left between the finger and the plate to permit the free introduction of a card edgewise under the finger and movement of the same along the plate to engage the side-edge gage. Although the form just described is that which is preferred, it is obvious that the card-holder may be formed in other ways without departing from the invention.

The card-holding finger may be arranged substantially midway between the top and bottom edges of the plate and the arm may conveniently be formed with its sides converging from the side-edge gage to the finger. In order to make the arm lighter in weight and to enable the surface of the card lying beneath the same to be seen, the arm may be cut away to as great an extent as may be possible without weakening the same sufficiently to render it ineffective.

Although the card-holder may be used in case a card is inserted at the rear of the platen, it is particularly adapted for use with a machine arranged for front insertion of the cards. In inserting a card, the right-hand lower edge may conveniently be introduced first and the card advanced until the left-hand edge is substantially in front of the card-holding finger when the card may be bent to the rear and swung to the left to carry its left-hand edge between the finger and the plate, such movement being continued until the left-hand edge is brought into contact with the side-edge gage. The card may also be advanced at the same time until the part on which the entry is to be

made is positioned at the writing line, which may be determined by the position of the wing scales. When the card has been positioned in this manner, the feed-rolls, which were cast off before the card was inserted at the front of the platen, may be returned to effective position. It should be understood that the card-holder of this invention is particularly adapted for use in connection with narrow cards.

Other features and advantages will hereinafter appear.

In the accompanying drawings,

Figure 1 is a fragmentary perspective view, showing the invention applied to the platen-frame of an Underwood Standard typewriter.

Figure 2 is a side view, partly in section, of the mechanism shown in Figure 1.

Figure 3 is a rear elevation, showing the means by which the attachment is supported on the platen-frame.

A platen 11 is mounted on a platen-axle 12, journaled in the ends 13 of the platen-frame, said ends being connected by a rear paper-table 14, which may be of the usual form. The portion of the rear paper-table lying beneath the platen is cut away to accommodate front feed-rolls 15 and rear feed-rolls 16, thus forming fingers 17 which extend upwardly a short distance at the front of the platen. Wing scales 18 are provided at the front of the platen, and their upper edges 19 are bent outwardly, as shown in the patent to Kunath, No. 817,923, granted April 17, 1906, to facilitate front insertion of cards or the like. The feed-rolls 15 and 16 may be cast off by any suitable means, such, for example, as shown in the patent to Jesse A. B. Smith, No. 1,378,627, granted May 17, 1921.

In carrying out the present invention, provision may be made of a plate 20, above the platen, bent upwardly at its left-hand edge to form a flange 21, which may serve as a side-edge gage for a card 22 inserted in the machine. From the upper edge of the gage, an arm or guard 23 extends to the right and is provided with a finger 24 extending toward the plate 20, but spaced therefrom sufficiently to permit the card to be slid freely between the finger and the plate, and the edge of the card brought into engagement with the flange or gage 21. The flange 21, arm 23 and finger 24 may be connected with the plate 20 in any desired manner, but, preferably, are formed from an extension of the plate bent into shape as desired. It should be understood that the spacing of the finger 24 from the plate is such that no gripping of the work-sheet is effected and that the plate 20 serves principally as a support for the gage 21 and arm 23 and as a means to guide the card under the finger 24 and to the gage 21.

The arm 23 is required to be only of sufficient strength to hold the upper part of the card to the rear to insure proper positioning of the same on the platen, to enable satisfactory typing thereon, and may be shaped and cut away so as to interfere as little as possible with the reading of printed matter which may be on the portion of the card lying back of the same. Preferably, the sides of the arm 23 converge as they extend from the gage, and the material of the arm is cut away as shown in Figure 1.

The plate 20 may be supported in any suitable manner, but, preferably, is supported in the same manner as the aligning plate 80 in said Patent, No. 1,378,627. Screws 25 extend through slots 26 in the plate 20 and are threaded into brackets 27 on the ends of arms 28, mounted on a shaft 29, which is journaled in brackets 30, secured to the ends 85 of the platen-frame. It will be seen that, due to the provision of the slots 26, the position of the plate 20 relative to the brackets 27 may be varied. A finger-piece 31, secured to the end of shaft 29, may be used to swing 90 the plate 20 upwardly when desired, as, for example, when the card-holder or attachment is not in use. Obviously, the card-holder or attachment herein disclosed may readily be attached to existing machines.

Each arm 28 comprises a portion 32, bent parallel to the shaft 29, and a portion 33, extending at right angles thereto, through which the shaft passes. It will be seen that this construction provides a bearing of 100 suitable length for each arm 28. To hold the arms 28 on shaft 29, so as normally to be fixed against rotation with respect thereto, provision is made of a cylindrical key 34 for each arm, mounted in slots 35 in the portion 33 and the parallel portion of the arm 28 and normally pressed into a groove 36 in the shaft 29 by means of a spring 37 supported on the portion 32 of the arm 28 which extends parallel to the shaft 29. In a like manner, the shaft 29 may normally be held in the position shown in Figure 2 by means of a cylindrical key 38, supported in slots 105 in the parallel arms of bracket 30 and pressed into a groove 39 in shaft 29 by means of a spring 40.

Obviously, the cards may be inserted over the rear paper-table 14 and carried around the platen to the printing line, where typing 110 may be effected by means of a type-bar 41 swinging upwardly and rearwardly to bring types 42 thereon against the platen. Preferably, however, the cards are inserted at the front of the platen. In such an operation, the feed-rolls 15 and 16 are cast off and the lower edge of the card inserted between the platen and the forwardly-inclined edges 19 of the wing scales 18 which guide the card into the throat or opening between the platen and the fingers 17 which are flared 115

outwardly to facilitate the introduction of the card, further insertion of the card 22 carrying its lower edge to a position over the rear paper-table 14, as shown in Figure 5. 2. When the card 22 has been partly inserted, the upper part thereof is swung to the rear, and the left edge of the card is passed between the finger 24 and the plate 20. The card is then moved to the left to bring its 10 left-hand edge against the gage 21 and the portion of the card on which typing is to be effected brought to the writing line by positioning the card with reference to the upper edges of the wing scales 18. In making such 15 an insertion, the card may be held diagonally, so that the lower right-hand corner is introduced first. In that case, the movement of the card behind the finger 24 and into engagement with the gage 21 involves 20 a swinging movement of the upper end of the card rather than a sidewise movement of the card as a whole. The feed-rolls 15 and 16 are then returned to the positions in which they co-operate with the platen, and 25 typing is effected in the usual manner by means of type-bars 41 and types 42.

Usually, only a single entry is made at each insertion. As soon, therefore, as the entry of an item has been completed, the 30 feed-rolls 15 and 16 are again cast off and the card 22 drawn out of the front of the machine. Another card may then be inserted, and, after adjustment by means of the side gage 21 and the wing scales 18, securely 35 held against the platen by returning the feed-rolls 15 and 16 to their normal effective positions. It will be evident that cards may be inserted and removed with very little delay, inasmuch as either insertion or removal 40 may be effected substantially by a single movement of the card, the casting off of the feed-rolls and their release being the only changes in the mechanism in connection with such insertion and removal.

45 In using different sizes of cards, it may occur that the finger 24 of the attachment will engage the card at one side of the central line thereof. This condition will result in a tendency of the card to twist and to slip 50 from the control of the finger. The plate 20, however, engages the rear face of the card and, by preventing a backward movement of the card at either side of the finger 24, prevents such a twisting movement and 55 consequent release of the card. It should be understood that the card-holder of this invention may be used to the best advantage with comparatively narrow cards.

60 Variations may be resorted to within the scope of the invention, and portions of the improvements may be used without others.

Having thus described my invention, I claim:

65 1. In a front-strike typewriting machine, in combination, a platen, and a card-con-

trolling device mounted above the platen comprising a plate extending longitudinally of the platen, a side-edge gage extending upwardly therefrom, and an arm extending from said side-edge gage parallel to the 70 plate and having a finger extending toward the plate but spaced therefrom to permit ready insertion of the card while engaging the front face thereof to hold the same against the platen at the printing line. 75

2. In a front-strike typewriting machine, in combination, a platen, feeding devices co-operating with the platen, and a card-holder to hold against the platen, at the printing line, a card inserted between the feeding 80 devices and the platen, said card-holder comprising a plate, positioned above the platen, an end gage bent up therefrom at one end, an arm bent over from said gage to extend parallel to the plate, and diminishing in width as it extends from said gage, 85 said arm being cut away, centrally thereof, to expose as much as possible of a card positioned thereunder without too great weakening of the arm, and a finger extending inwardly from the end of said arm to engage the outer face of the card, but spaced from said plate to enable the insertion of the side edge of the card without interference. 90

3. In a front-strike typewriting machine, in combination, a platen, feeding devices co-operating with the lower part of said platen and adapted for the front insertion of a card, and card-holding means comprising a side-edge gage positioned above the platen for use in adjusting the upper part of an inserted card when the latter is bent rearwardly from the plane of front insertion, a finger back of which the card may be moved in bringing the same into engagement with the side-edge gage, said finger being so positioned that the card, when moved to the rear thereof, will be held thereby against the platen at the printing line, and a support extending transversely of the machine to engage the rear face of the card held by the finger, so as to counteract any twisting tendency of the card, due to engagement thereof by the finger at one side of the center line thereof. 110

4. In a front-strike typewriting machine, in combination, a platen, feeding devices co-operating with the lower part of the platen, a card-controlling device above the platen comprising a plate extending longitudinally of the platen, a side-edge gage extending upwardly therefrom, and an arm projecting from said side-edge gage parallel to the plate and having a finger extending toward the plate but spaced therefrom to permit ready insertion of the card therebehind and acting to hold the card against the platen at the printing line while held between said platen and the feeding devices, and a mount- 120 125 130

ing for said card-controlling device whereby the latter may be shifted as a whole from effective to ineffective position, and vice versa.

5. In a front-strike typewriting machine, in combination, a platen, a rear paper-table having fingers extending beneath the platen, releasable feed-rolls positioned to co-operate with the platen in the openings between said

10 fingers, wing-scales bent outwardly at their upper edges to facilitate front insertion, and a card-controlling device comprising a side-edge gage, and means to hold the upper end of an inserted card in a rearward position to cause proper positioning of the card on the platen at the printing line comprising an arm extending from said gage parallel to the platen-axis, so that its end will engage the front face of the card at a substantial distance from said side-edge gage.

6. In a front-strike typewriting machine, in combination, a platen, a platen-frame, feeding devices co-operating with the lower part of the platen and adapted for the 25 front insertion of a card, and a card-controlling device above the platen comprising a plate extending longitudinally of the platen, a side-edge gage extending upwardly from the plate, near one end of the 30 platen-frame, and an arm extending from the upper part of said gage parallel to said plate toward the middle of the platen-frame, whereby a narrow card inserted diagonally at the front of the platen with 35 its upper end inclined away from said side-edge gage may be bent rearwardly above the platen and swung sidewise between the plate and the arm into contact with said side-edge gage.

40 7. In a front-strike typewriting machine, in combination, a platen, a platen-frame, feeding devices co-operating with the lower part of the platen and adapted for the front insertion of a card, and a card-holding device above the platen comprising a plate 45 extending longitudinally of the platen, a side-edge gage extending upwardly from the plate, near one end of the platen-frame, an arm extending from the upper part of said gage parallel to said plate toward the 50 middle of the platen-frame, and a finger extending inwardly from the end of the

arm and spaced from said plate sufficiently to permit edge insertion of the card without interference therewith, whereby a narrow card inserted diagonally at the front of the platen with its upper end inclined away from said side-edge gage may be bent rearwardly above the platen and swung sidewise between the plate and the arm into contact with said side-edge gage.

8. In a front-strike typewriting machine, in combination, a platen, a platen-frame, feeding devices co-operating with the lower part of the platen and adapted for the 65 front insertion of a card, a card-controlling device above the platen comprising a plate extending longitudinally of, and normally tangentially to, the platen, a side-edge gage extending upwardly from the plate, near 70 one end of the platen-frame, an arm extending from the upper part of said gage parallel to said plate toward the middle of the platen-frame, and a finger extending inwardly from the end of the arm and 75 spaced from said plate sufficiently to permit edge insertion of the card without interference therewith, whereby a narrow card inserted diagonally at the front of the platen with its upper end inclined away 80 from said side-edge gage may be bent rearwardly above the platen and swung sidewise between the plate and the arm into contact with said side-edge gage, and a mounting for said card-controlling device 85 whereby the latter may be shifted as a whole from normal or effective to ineffective position, and vice versa.

9. In a front-strike typewriting machine, in combination, a platen, card-guiding 90 means for facilitating the front insertion of a card bottom foremost, and a card-controlling device above the front of the platen comprising a side-edge gage and an arm arranged to engage the outer face of the inserted card positioned against the side-edge gage so as to hold the same against the platen at the printing line while various lines are being written upon the card.
